TRUSS

Filed March 16, 1938

UNITED STATES PATENT OFFICE

2,171,905

TRUSS

Emil George Barnhard, Philadelphia, Pa., assignor to The Hastings and McIntosh Truss Co., a corporation of Pennsylvania

Application March 16, 1938, Serial No. 196,269

1 Claim. (Cl. 128—105)

One of the objects of my invention is to provide a truss which may be worn with comfort and at the same time be efficient for the purposes intended.

5 Another object of my invention is to provide a truss that may be readily adjusted to the person of the wearer.

Another object of my invention is to provide a truss in which the pads are held in their proper 10 position under the influence of the resilient member on which they are mounted; and with these and other objects in view my invention consists of the parts and combination of parts herein-after pointed out.

15 Another object of my improved truss is to hold the hernia by pad pressure from the front of the truss frame instead of through the body of the wearer from the back to the front.

Another object of my invention is to eliminate 20 all irritating and unwieldy back pads by crossing the straps which provide the frame work, or body of the truss frame, and which serve as carriers for the metal side sub-frames.

In the drawing:

25 Figure 1 is a perspective view of my improved truss.

Figure 2 is a detail top plan view.

Figure 3 is a perspective view of the spring metal parts of my improved truss detached.

30 Figure 4 is a vertical transverse sectional view on the line 4—4, Figure 1.

The reference numeral 1 designates the hip members of the truss in which are embedded suitable springs 2. These hip members terminate at one end in back straps 3 and end straps 35 4. These end straps 4 are provided with what I term buttonholes 5 which are adapted to engage the fasteners 6 of which there are one or more, as desired, on each hip member. Preferably a strip of leather 7 is attached to the outside of each hip member.

The hip members are connected at their forward ends by a flat spring 8, the ends of which are suitably secured to the forward ends of the hip members and of the springs 1 by means of the fasteners 9.

5 The spring 8 is normally bent inward from its ends toward the middle 10 toward the body of the wearer, and are provided with elongated slots 11. The pads 12, of any desired construction, are secured to the spring 8 by suitable 10 means 13 mounted in the elongated slots 11 and may be adjusted to the desired position.

It will be noted by reason of the spring 8 being bent inward normally that the pads may be held firmly in their proper place irrespective 15 of any movement of the hip members and resist displacement under the influence of the muscles of the abdomen.

When these straps are crossed and the ends fastened in place the truss is resting securely 20 on the body and can not be displaced from its proper position by body movements.

My improved truss rests securely on the body without binding at the hips, with full front pressure, and without irritating the body.

25 The adjusting screws 13 are provided with rings 14 whereby the user may readily manipulate the pads to the proper position.

What I claim is:

A truss comprising resilient hip pieces, fastening elements on said pieces each terminating in a combined back and side strap, button holes or other fastening elements in the free ends of said straps designed for engagement with said fastening elements, a flat resilient member connecting the forward ends of said hip pieces and normally bowed inwardly from end to end 30 pads adjustably mounted on the inner face of said flat member.
